W. A. GARRATT.
PNEUMATIC HORN.
APPLICATION FILED JAN. 30, 1920.

1,391,887.

Patented Sept. 27, 1921.

Inventor:

Walter A. Garratt

FIG. 2. By *Allen L. Teller*
Attorneys.

UNITED STATES PATENT OFFICE.

WALTER A. GARRATT, OF COVINGTON, KENTUCKY.

PNEUMATIC HORN.

1,391,887.

Specification of Letters Patent. Patented Sept. 27, 1921.

Application filed January 30, 1920. Serial No. 355,058.

To all whom it may concern:

Be it known that I, WALTER A. GARRATT, a citizen of the United States, and a resident of Covington, in the county of Kenton and State of Kentucky, have invented certain new and useful Improvements in Pneumatic Horns, of which the following is a full, clear, and exact description, reference being had to the accompanying drawings, forming a part 10 of this specification.

My invention relates to horns for use particularly with motor vehicles, and which are adapted to be operated by suction from the intake manifold of the engine, although with 15 modifications such horns may be employed with air pressure generated in the engine exhaust.

It is the object of my invention herein to provide a sounding device which can be 20 readily and easily adjusted for various tone values and particularly to give a most harsh and raucous tone. The device operates on a principle discovered by me, wherein a member corresponding to a membrane or 25 diaphragm operates as a reed to generate the tone, said tone being modified by additional devices employed in connection with said tone generating member.

Among other things the additional devices 30 are carried preferably on the generating member itself, whereby the movement of the member sets up a vibration in the carried device which re-acts to modify the air vibrating function of the member, and at the same 35 time sets up dissonant vibrations of the member itself.

Furthermore the valve element which 40 co-acts with the generating member is resiliently carried, so as to have a partial movement along with the said member, and thereby further disturb the quality of sound vibrations and hence tone production.

The elements referred to above and the 45 functions noted, I accomplish by that certain construction and arrangement of parts to be hereinafter more specifically pointed out and claimed.

In the drawings, Figure 1 is a central cross section through the device in which to clearly 50 indicate the structure, the thickness of some of the parts is somewhat out of proportion to the other parts. Fig. 2 is a perspective view of the one side of the sound generating member. Fig. 3 is a perspective view of the 55 other side thereof.

The device has a sound projecting horn 1, and a back plate 2. The sound generating element in the form of a relatively thin and vibrant disk 3, is supported between the sound projecting device and the back plate. 60 There are gaskets 4 intermediate the projector base 1^a and the disk, and a fairly thick gasket assembly 5 between the disk and the back plate, the parts being held together by means of bolts 6 passing through 65 the assembly, peripherally of the projector, the back plate, the disk and the gaskets.

This construction leaves an air chamber 3^a between the disk and the back plate, and an air conduction pipe 7 passes through the 70 back plate into this chamber, said pipe being connected by suitably valved conduit pipes to the intake manifold of an engine (not shown).

The disk has a central aperture through 75 which any air admitted from without to the chamber behind said disk, must pass, and there is firmly united around the periphery of this aperture an annular member 8, which has a cylindrical flange 9 extending out- 80 wardly from the outer surface of the disk, and serves as a valve seat in the operation of the device, as will be noted.

Mounted near the periphery and point of attachment of the disk on the inside of the 85 chamber, so as not to affect the disk vibration, is a spring arm 10, which carries at its inner end, at the axis of the disk, and the center of the aperture therein, a screw 11. This screw is held adjustably in place by 90 means of a nut 12 on one side of the arm, and a nut 13 on the other.

The screw projects through the aperture in the disk and carries at its end, on the outside of the chamber, a valve 14 in the shape 95 of a disk, provided with suitable means on the inner side thereof, to seat against the annular valve seat member about the disk aperture. The valve lies inside of the cylindrical flange of said seat.

The center of the back plate is provided with a boss, within which screws an adjusting screw 15. The nut 12 of the valve carrying spring arm, plays rearwardly in the hole of the boss, and the screw 15 acts as 100 an abutment for the nut 12, thereby limiting the movement of the spring arm, and the valve carried by it, to the desired degree.

With the parts as so far described it will be evident that upon suction being applied to 110

the inlet pipe in the back plate, the air in the chamber 3^a will be exhausted and the disk drawn inwardly into the chamber.

When this occurs, the valve moves inwardly slightly also, with the adjusting screw serving as the limit of the motion, and the resilience of the spring arm accomplishing the inward motion. As can be seen the comparative resilience of the 10 spring arm and the disk will regulate the nature of the motion of the valve with said disk.

Suffice it to say that there will be an opening of the space between the valve and its 15 seat on the disk, either at the instant that the valve nut strikes its abutment or just before this, due to the superior speed of the disk.

At the rebound of the disk the valve will 20 be carried with it, and the continued motion of the disk to and fro, with great rapidity will set up air vibrations, which project themselves through the sound projector member of the device, and the nature of the 25 sound may or may not be dissonant due to the travel of the valve with the disk as above described.

In addition, as heretofore noted, I apply 30 to the outer surface of the disk, a vibratory mechanism which re-acts against the disk, and not only effects its vibratory function, but in addition sets up vibrations in the disk itself, which further add a very raucous tone to the sound produced.

35 This mechanism comprises a yoke 16 clamped at the center between the annular valve member 8 and the disk 3, and thus rigid with the disk. The radial arms of the yoke are however elevated from the surface 40 of the disk so as not to impair its vibrations.

To the outer ends of the yoke are connected the ends of an arched spring 17. At the center of this spring is secured a fairly heavy cap 18, having depending flanges 19. 45 The cap is held in place by means, preferably of a screw 20 and a nut 21, and the flanges 19 lie in normal position slightly elevated above the flange projecting from the annular valve seat of the disk.

50 This device thus not only acts as a vibratory weight against the operation of the disk, but it also strikes against the flanges of the disk valve seat, thereby setting up vibrations of the disk itself, which vary 55 from those imparted to it, by its own motion.

The sound produced by this mechanism is of a peculiarly penetrating and disagreeable character, and acts as a startling warning 60 when used in connection with a motor vehicle. It is also adapted to be used in the desired sizes in the place of fire signal warnings or other forms of signals and alarms, in which it is desired to attract attention 65 with a sound of strikingly different nature

from those usually heard by the persons within the sound radius.

By failure in the above matter to indicate the possibility of the use of mechanical equivalents for the parts described, I do not 70 wish to imply limitations to the claims that follow, in the construction of which, it is my desire that the doctrine of equivalents be fully applied.

Having thus described my invention what 75 I claim as new and desire to secure by Letters Patent, is:

1. In a sounding device, means for peripherally supporting a vibrant disk, means for applying suction behind said disk, said disk 80 having at least one opening therein, a valve device of which said opening forms a part, and vibratory mechanism carried by the disk, to modify the vibrations thereof.

2. In a sounding device, means for peripherally supporting a vibrant disk, means for applying suction behind said disk, said disk having at least one opening therein, a valve device of which said opening forms a part, and vibratory mechanism carried by the disk, 90 to modify the vibrations thereof, said vibratory mechanism being carried centrally of the disk.

3. In a sounding device, means for peripherally supporting a vibrant disk, means for 95 applying suction behind said disk, said disk having at least one opening therein, a valve device of which said opening forms a part, and vibratory mechanism carried by the disk, to modify the vibrations thereof, said vibratory mechanism being located to strike the disk during its vibrations to additionally set up vibrations of the disk itself.

4. In a sounding device, means for peripherally supporting a vibrant disk, means for 105 applying suction behind said disk, said disk having an opening therein, and a closure for said opening adapted to act together with said opening as an air valve, said closure being resiliently carried, so as to modify the vibrations of air passing through said valve.

5. In a sounding device, means for peripherally supporting a vibrant disk, means for applying suction behind said disk, said disk 115 having an opening therein, and a closure for said opening adapted to act together with said opening as an air valve, said closure being resiliently carried, so as to modify the vibrations of air passing through said valve, and an abutment for the said resilient closure member, to cause its positive separation from the disk opening at the desired point.

6. In a sounding device, means for peripherally supporting a vibrant disk, means for applying suction behind said disk, said disk having an opening therein, and a closure for said opening adapted to act together 125 with said opening as an air valve, said clo- 130

sure being resiliently carried, so as to modify the vibrations of air passing through said valve, and an abutment for the said resilient closure member, adjustable to cause its positive separation from the disk opening at the desired point.

7. In a sounding device, means for peripherally supporting a vibrant disk, means for applying suction behind said disk, said disk having at least one opening therein, a valve device of which said opening forms a part, and vibratory mechanism carried by the disk, to modify the vibrations thereof, said vibratory mechanism comprising in part a substantially heavy member, supported on a spring.

8. In a sounding device, means for peripherally supporting a vibrant disk, means for applying suction behind said disk, said disk having at least one opening therein, a valve device of which said opening forms a part, and vibratory mechanism carried by the disk, to modify the vibrations thereof, said vibratory mechanism comprising in part a substantially heavy member, supported on a spring, and means on said heavy member spaced from the disk sufficiently to strike it upon conjoint vibratory movement with the disk, for the purpose described.

30 9. In a sounding device, means for peripherally supporting a vibrant disk, means for applying suction behind said disk, said disk having at least one opening therein, a valve device of which said opening forms a part, and vibratory mechanism carried by the disk, to modify the vibrations thereof, said vibratory mechanism comprising a member mounted centrally of the disk, an arched spring on said member, a weighted element on the arched spring, and flanges or the like from the weighted member lying at their ends in proximity to the disk, as and for the purpose described.

10. In a sounding device, means for peripherally supporting a vibrant disk, means for applying suction behind said disk, said disk having an opening therein, and a closure for said opening adapted to act together with said opening as an air valve, said closure being resiliently carried, so as

to modify the vibrations of air passing through said valve with the closure and its mounting comprising a spring arm secured adjacent the periphery of the disk, and a supporting member mounted at the end of the spring arm and extending through the disk aperture, said supporting member having thereon a small disk adapted to seat in the aperture of the disk, on the atmospheric air side of said disk.

11. In a sounding device, means for peripherally supporting a vibrant disk, means for applying suction behind said disk, said disk having an opening therein, and a closure for said opening adapted to act together with said opening as an air valve, said closure being resiliently carried, so as to modify the vibrations of air passing through said valve with the closure and its mounting comprising a spring arm secured adjacent the periphery of the disk, and a supporting member mounted at the end of the spring arm and extending through the disk aperture, said supporting member having thereon a small disk adapted to seat in the aperture of the disk, on the atmospheric air side of said disk, said supporting member being adjustable to control the spring pressure of the arm.

12. In a sounding device, means for peripherally supporting a vibrant disk, means for applying suction behind said disk, said disk having an opening therein, and a closure for said opening adapted to act together with said opening as an air valve, said closure being resiliently carried, so as to modify the vibrations of air passing through said valve with the closure and its mounting comprising a spring arm secured adjacent the periphery of the disk, and a supporting member mounted at the end of the spring arm and extending through the disk aperture, said supporting member having thereon a small disk adapted to seat in the aperture of the disk, on the atmospheric air side of said disk and an adjustable abutment for the supporting member mounted on the suction side of the disk.

WALTER A. GARRATT.
